A. v. Briesen

UNITED STATES PATENT OFFICE.

HENRY A. BRADLEY, OF NEW YORK, N. Y.

HYDROCARBON-BURNER.

SPECIFICATION forming part of Letters Patent No. 233,397, dated October 19, 1880.

Application filed May 26, 1880. (No model.)

To all whom it may concern:

Be it known that I, HENRY A. BRADLEY, of New York, in the county and State of New York, have invented a new and useful Improvement in Burners for Hydrocarbon Fuel, 5 of which the following is a specification.

Figure 1 is a top view, partly in section, of my improved burner, and Fig. 2 is a vertical central section of the same.

10 This invention relates to certain improvements on Patent No. 217,259, granted to me on the 8th day of July, 1879; and it consists, principally, in providing the spindle-valve therein described with a screw-thread for moving it 15 up or down at a point below and with a stuffing-box above the valve portion proper.

The invention also consists of other details of improvement, which are hereinafter more fully specified.

20 In the accompanying drawings, the letter A represents the shell of my improved burner, which I now make in one piece with the bottom plate, C; but the top plate, B, is fastened down by means of bolts *a a*, that pass through 25 ears *b*, that project inwardly from the shell. By this means I am able to remove the plate B even if the valve-spindles are screwed up, which the former construction did not enable me to do, and I now can open the shell even 30 if one of the spindles sticks fast in its raised position. In every other respect the shell with its subdivisions is substantially as in the other patent, forming an upper larger chamber, *d*, and a lower annular chamber, *e*.

35 F F are the valve-spindles, of which either one or more may be used, and which extend upward through the partition D and into or against the top plate, B. Part of each valve-spindle is screw-threaded, but not as in my 40 former patent, where it passes through the partition D, for in this partition I have now placed

a packing-box, *f*, that embraces the spindle and prevents steam from passing around it into the chamber *d*. The screw-thread is now put upon the lower part of the spindle—that 45 is to say, below the valve proper, *g*—so as to screw into the partition C or into a cap, *h*, placed into said partition. The valve portion *g* has apertures, and operates against a valve-seat in the partition D, as heretofore. Thus, 50 by turning the spindle by a suitable instrument, taking hold of its lower end, it will be moved up or down to reduce or enlarge the discharge-orifice for the hydrocarbon, and yet will always move in the packing-box *f*, so that the 55 steam in the chamber *e* will effect its legitimate function only, and not mingle with the liquid fuel in chamber *d*. The compression-nut of each packing-box *f* becomes accessible by lifting the plate B, and the several nuts of said 60 packing-boxes are prevented from turning spontaneously by suitable nut-locks *i*, placed into the chamber *d*, as shown in Fig. 1.

I claim—

1. The combination of the shell A, containing chambers *d* and *e*, with the partly-hollow spindle-valve *F*, having projecting valve *g*, and with the packing-box *f*, above the valve proper, *g*, and with a nut in the lower plate, C, the spindle-valve having a screw-thread below 70 said valve proper, substantially as specified.

2. The combination of the shell A, which is made in one piece with the bottom plate, C, with the removable top plate, B, fastening-bolts *a*, and packing box or boxes *f*, and one 75 or more vertically-movable spindle-valves, substantially as specified.

HENRY A. BRADLEY.
